Attorney

UNITED STATES PATENT OFFICE.

THOMAS OWEN, OF HOUSTON, TEXAS, ASSIGNOR OF ONE-HALF TO THOMAS J. BAKER AND JACOB V. DEALY, OF SAME PLACE.

RULING-MACHINE.

SPECIFICATION forming part of Letters Patent No. 594,808, dated November 30, 1897.

Application filed May 25, 1897. Serial No. 638,124. (No model.)

To all whom it may concern:

Be it known that I, THOMAS OWEN, a citizen of the United States, residing at Houston, in the county of Harris and State of Texas, 5 have invented certain new and useful Improvements in Ruling-Machines; and I do declare the following to be a full, clear, and exact description of the invention, such as will enable others skilled in the art to which it applies to make and use the same.

My invention has relation to ruling-machines designed for the use of engravers and draftsmen.

The object of the invention is to provide a 15 machine of this character by means of which engravers may cut horizontal, inclined, or circular lines into the plate, or draftsmen draw the same lines upon a sheet of drawing.

With this object in view the invention consists of certain features of construction and combination of parts which will be herein-after fully set forth and claimed.

In the accompanying drawings, Figure 1 is 25 a perspective view of my complete instrument. Fig. 2 is a longitudinal sectional view on the line xx of Fig. 1, and Fig. 3 is a cross-section on the line yy of Fig. 1.

In said drawings, 1 denotes the longitudinal track, one end of which is supported in a post 30 2, journaled in a standard 3, adapted to be attached to a table by screws 4 or the like. The other end of this track 1 is provided with a foot-piece 5, having a thumb-screw 6, by means of which the track is adapted to be held to the table in its proper adjustment. This foot-piece has its upper end projecting 35 a slight distance above the track, and connecting this upper end with the post is a rod or wire 7.

8 denotes a carriage, which consists of a standard 9, having a grooved base 10, adapted to embrace the tubular track 1 and be held thereto or permitted to reciprocate thereon by a set-screw 11. This carriage is provided 45 with a lateral extension 12, having a standard 13 in line with a standard 14, projecting upwardly from the carriage. Journaled in the standards 13 and 14 is a screw-shaft 15, on the end of which is secured a ratchet-wheel 50 16, provided with a crank-handle 17, by means of which it is rotated and the parts quickly ad-

justed. 18 denotes a ratchet-lever suitably connected with the standard 14 for rotating the wheel tooth by tooth for a purpose presently to appear. 19 denotes a beam which is carried by said carriage and has bolted to its forward end a head 20, to which the tool-supporting bar 21 is journaled, said bar being rotated by the crank-wheel 22, locked against rotation by a set-screw 23 and adjusted in 60 the direction of its length by a set-screw 24. One end of this tool-bar is provided with a clamp 25 to hold an engraving-tool or a pen or pencil 26, and above this clamp and at the same end of the bar is secured a frame 27, 65 supporting a lens 28, to enable the operator to make very fine lines.

28' denotes a nut fitted to the screw-shaft 15 and having its lower end slotted and embracing the beam 19, to which it is adjustably secured by a set-screw 29.

30 denotes a pulley secured to the post 2 and provided with a crank 31. Wound around and secured to this pulley is a rope or connection 32, one end of which is connected to 75 the carriage at 33 and the other end of which extends to the foot-piece 5, is rove around a pulley 34, journaled to the foot-piece, and then led back and connected at 35 to the carriage. By rotating the crank 31 and its 80 wheel it is evident that the carriage will be moved longitudinally of the track 1.

The operation of the device is as follows: When it is desired to draw or cut straight lines, the standard 3 is secured to the table 85 and the foot-piece 5 is also secured to the table after the machine or implement has been adjusted over the work. The bar 21 is first clamped securely to the head 20 by the set-screws 23 and 24. The crank 31 is now rotated back and forth, and the tool or pencil at the end of the bar 21 will be reciprocated, and at the end of each line, by working the ratchet-lever 18 a tooth or more, the spaces between the lines may be varied. If now it be desired to draw or cut lines at an angle to those drawn or cut, by loosening the thumb-screw 6 and swinging the foot end of the track in the desired direction the lines may be made at angles to those already made. 90 When it is desired to make circular work, the set-screw 11 is worked to clamp the car- 95 100

riage to the track 1, the set-screws 24 loosened, and the bar 21 moved in or out, according to the circle to be made. The set-screw 24 is then clamped to hold the bar in its extended adjustment and the set-screw 23 is loosened. Now by rotating the crank-wheel 22 the tool or pencil at the end of the bar will cut or draw a curved line, and if it be desired to cut parallel curved lines by operating the ratchet-lever 18 this may be accomplished.

From the foregoing description, taken in connection with the accompanying drawings, the construction, operation, and advantages of the invention will be readily understood without requiring further explanation.

The device is exceedingly simple in construction, strong in parts, and may be placed upon the market at comparatively small cost.

While I have shown and described the preferred embodiment of my invention, I would have it distinctly understood that I contemplate and reserve to myself the right to make such changes as fall within the scope of my claims.

Having thus described my invention, what I claim, and desire to secure by Letters Patent, is—

1. In an instrument of the character described, the combination with the track, of a carriage mounted to reciprocate thereon, a beam having a sliding engagement in said carriage, means for sliding said beam lengthwise, said beam being provided with a head, and a tool-bar rotatably connected with said head, and provided with means for locking it, substantially as set forth.

2. In an instrument of the character described, the combination with the track, of a carriage mounted to reciprocate thereon, a

beam having a sliding engagement in said carriage, a ratchet-wheel carried by said carriage and provided with a screw-shaft, a nut engaged with said screw-shaft and adjustably connected with said beam, said beam provided with means for clamping and holding a tool or pencil, substantially as set forth. 45

3. In an instrument of the character described, the combination with a standard, of a track hinged thereto, a carriage supported 50 to slide lengthwise of said track, means for reciprocating said carriage, a beam carried by said carriage, a tool or pencil supporting bar, means for connecting said bar to the beam, and means for rotating said bar, substantially as set forth. 55

4. In a tool of the character described, the combination with the standard, a post journaled therein, a pulley journaled on said post, a track connected to said post and provided at its outer end with a foot having means for fastening it stationary, a carriage adapted to slide on said track, a cord or connection wound about said pulley and having one end secured to the carriage at one point 60 and the other end passing around a sheave journaled to the outer end of the track and secured to the carriage at another point, and a beam having a head at one end, means for longitudinally adjusting the beam, and a tool 65 or pencil bar rotatably connected with said head and provided with means for fixing the tool-bar to said head, substantially as set forth.

In testimony whereof I hereunto affix my 75 signature in presence of two witnesses.

THOMAS OWEN.
